Primary Examiner—Dominic Simone

[57] CLAIM

The ornamental design for a puzzle, as shown, described and demonstrated.

DESCRIPTION

FIG. 1 is a top plan view of my puzzle showing my new design;

FIG. 2 is a bottom plan view thereof;

FIG. 3 is a front elevation view thereof, the left side elevation view, the right side elevation view, and the rear side elevation view being identical;

FIG. 4 is a top plan view of the puzzle pieces shown separately for clarity of illustration;

FIG. 5 is a top plan view of the puzzle tray shown separately for clarity of illustration;

FIG. 6 is a top plan view of the puzzle pieces in an alternate configuration, shown separately for clarity of illustration;

FIG. 7 is a top plan view of the puzzle pieces in an alternate configuration, shown separately for clarity of illustration;

FIG. 8 is a top plan view of the puzzle pieces in an alternate configuration shown separately for clarity of illustration;

FIG. 9 is a top plan view of the puzzle pieces in an alternate configuration, shown separately for clarity of illustration;

FIG. 10 is a top plan view of the puzzle pieces in an alternate configuration, shown separately for clarity of illustration;

FIG. 11 is a top plan view of the puzzle pieces in an alternate configuration, shown separately for clarity of illustration;

FIG. 12 is a top plan view of the puzzle pieces in an alternate configuration, shown separately for clarity of illustration;

FIG. 13 is a top plan view of the puzzle pieces in an alternate configuration, shown separately for clarity of illustration;

FIG. 14 is a top plan view of the puzzle pieces in an alternate configuration, shown separately for clarity of illustration; and,

FIG. 15 is a top plan view of the puzzle pieces in an alternate configuration, shown separately for clarity of illustration.
